CHILD'S TRUNKS

Frances D. Walter and Marie Walter Michael,
Charlotte, N. C.

Application October 18, 1949, Serial No. 122,074

3 Claims. (Cl. 128—287)

1

This invention relates to children's garments and more especially to a garment such as a pair of children's trunks having means therein for holding an absorbent disposable pad or a diaper.

It is an object of the invention to provide a child's garment such as a pair of trunks which may be secured around the child's body by any suitable means such as snap fasteners and which has means suspended from the front and rear inner surfaces of the garment over which a diaper or the like may be folded so that the diaper will fit snugly around the child when the garment is secured on the child.

It is another object of this invention to provide means for suspending a diaper or the like within a pair of trunks without the use of pins or the like in such a manner as to hold the diaper securely and to prevent the diaper from chafing the wearer.

It is still another object of this invention to provide means for suspending a diaper or the like within a child's garment in such a manner as to permit its easy removal from the garment.

Some of the objects of the invention having been stated, other objects will appear as the description proceeds, when taken in connection with the accompanying drawings in which:

Figure 1 is an isometric view of the garment showing the same as worn by a child, a portion of the body of the child being shown in dotted lines;

Figure 2 is an enlarged plan view of the garment in unfolded position and showing the manner in which a diaper is secured therein.

Figure 3 is an enlarged exploded sectional view taken along the line 3—3 in Figure 2 and showing the manner in which the upper edge of the garment is reinforced and the manner in which a depending tape is secured thereto.

Figure 4 is an enlarged exploded sectional view taken along the line 4—4 in Figure 2 and showing the manner in which a diaper is folded around transverse tapes to secure the same within the garment.

Referring more specifically to the drawings the numeral 10 broadly designates a child's garment such as a pair of trunks which is shown as being of substantially an hour glass shape when unfolded and which has a front portion 11 and a back portion 12. The trunks 10 are cut away as at 13 and 15 midway of each side thereof to provide openings through which the legs of a child 16 may extend.

The trunks 10 are preferably made of two layers of material, the outer layer indicated at

5

17 (Figures 3 and 4) preferably being of fabric and the inner layer indicated at 18 preferably being of a waterproof material. The upper front or left-hand edge of the trunks, in Figure 2, is provided with a reinforcing hem which is formed by the two layers of material 17 and 18 being turned over at their upper edges and having a turned under portion of a tape 20 sewn thereto by stitches 21 (Figure 3). The other edge of the tape 20 is penetrated by stitches 22 which extend through a pair of depending tapes to be presently described and penetrate the inner and outer layers of material 18 and 17 to thus securely bind the upper edge of the trunks.

15

The front sides 25 and 26 and the back sides 27 and 28 are reinforced in a similar manner by tapes 30, indicated by dotted lines in Figure 2, which are sewn between the inner layer of material 18 and the outer layer of material 17 along a line of stitches 31. The line of stitches 31 extends along the full length of the trunks on each side thereof and thus extends around the edge of the cut away portions 13 and 15 to bind the two layers of material together at the cut away portions.

25

By referring to Figure 4 it will be observed that the upper back or right-hand edge in Figure 2 of the trunks is reinforced in a manner similar to the manner in which the front edge is reinforced. The outer layer of material 17 and the inner layer 18 are turned over at their upper edges and a turned under portion of a tape 32 is sewn thereto by stitches 33. The other edge of the tape 32 is penetrated by stitches 35 which extend through a pair of depending tapes, to be presently described, and penetrate the inner and outer layers of material 18 and 17 to thus securely bind the back upper edge of the trunks. An elastic tape 36 is preferably secured between the tape 32 and the turned over portions of the inner and outer layers of material 18 and 17 as by stitches 37 and 38. The elastic tape 36 serves to gather the upper back portion of the trunks 10 and to assist in holding the same snugly against the body of a wearer.

35

Suitable snap fasteners 40 are provided along the front and back edges of the trunks 10 so that the trunks may be folded around the body of a child 16 and the snap fasteners 40 may be snapped together to secure the trunks around the child 16 as shown in Figure 1. The lowermost of the snap fasteners 40, in Figure 1, may be left unfastened, if desired to provide larger holes through which the legs of the child extend.

40

Means are provided at the front and back of

2

the trunks for securing a diaper or the like within the trunks and since these means are identical only the means at the front of the trunks will be described, the same reference characters with the prime notation added applying to the means at the back of the trunks.

A pair of depending tapes 41 and 42 which may be of any suitable material such as fabric, or elastic, or plastic or the like are secured at their upper ends to the upper edge of the trunks 10 by means of the stitches 22 which also secure the tape 20 to the layers of material 17 and 18. By referring to Figure 3, it will be observed that the tape 41 is disposed between the tape 20 and the inner layer of material 18 and is folded to provide an upper portion 41a and a lower portion 41b. The tape 42 is folded in a like manner. Tapes 41' and 42' are secured to the back upper edge of the trunks 10 in a like manner by the stitches 35 which secure the tape 32 to the back edge of the layers of material 17 and 18, and these tapes 41' and 42' are folded like the tapes 41 and 42.

The depending tapes 41 and 42 are spaced apart from each other a distance approximately equal to the width of the trunks at their narrowest point between the cut away portions 13 and 15 and are provided with a plurality of transverse tapes 45 which extend between the tapes 41 and 42 and are secured at one end between the upper portion 41a and the lower portion 41b of the tape 41 by stitches 46. The other end of the tapes 45 are secured to the tape 42 in a like manner by stitches 47. It is thus seen that the tapes 41, 42 and 45 and the tapes 41', 42' and 45' form a pair of ladder-like suspension means for holding an absorbent disposable pad or diaper 50 within the trunks 10.

The diaper 50 is folded into a rectangular shape and one end thereof is placed over the tapes 45 at the front portion 11 of the trunks 10 and is then folded back under the uppermost of the tapes 45 and alternately over and under the other of the tapes 45 to hold the diaper 50 securely in a desired position. The other end of the diaper 50 is folded over the tapes 45' at the back portion 12 of the trunks 10 in a like manner to thus hold the diaper 50 securely within the trunks 10 and to cover the tapes 45 and 45' so that they will not come into contact with the body of a wearer when the trunks are worn. Further, the manner in which the diaper 50 is folded over the tapes 45 and 45' causes the diaper 50 to lie flat and thus it will not chafe a child wearing the trunks 10.

It is thus seen that the diaper 50 may be disposed within the trunks 10 as described and the trunks with the diaper therein may be placed around the body of a child and secured by the snap fasteners 40 as shown in Figure 1, and the diaper 50 will be held securely in place without the aid of pins and the like and will be hidden

from view by the trunks 10. When it is desired to change the diaper 50 it may be easily removed from the tapes 45 and 45' and a fresh diaper may be folded over the tapes 45 and 45' in the manner described.

It is thus seen that there is provided a child's garment having means therein for removably securing a diaper or the like in such a manner as to hold the diaper securely and at the same time prevent the same from chafing the body of the wearer and which diaper may be easily removed and a fresh diaper inserted within the garment.

In the drawings and specification there has been set forth a preferred embodiment of the invention, and although specific terms are employed, they are used in a generic and descriptive sense only, and not for purposes of limitation, the scope of the invention being defined in the claims.

20 We claim:

1. In a child's garment having front and back portions, means for securing a diaper therein comprising a pair of tapes secured to and depending from the front and back portions of the 25 garment, and a plurality of spaced transverse tapes secured to the depending tapes whereby the opposed ends of a diaper may be folded over the transverse tapes at the front and back portions of the garment.

30 2. In a child's garment having front and back portions and being of hour glass formation in plan, snap fastening means on the edges of the garment for securing the front and back portions together, spaced depending tapes secured 35 to and depending from the front and back portions of the garment, and a plurality of spaced transverse tapes secured to the depending tapes whereby a diaper may have its ends folded over and under the transverse tapes at the front and 40 back of the garment to hold the diaper in position within the garment.

3. In a child's garment having a front and back portions and being of hour glass formation in plan, means for adjustably securing the back 45 and front portions together, a pair of spaced depending tapes secured at one of their ends to the inner front portion of the garment and depending therefrom, a second pair of depending tapes secured at one of their ends to the inner back 50 portion of the garment, the other ends of said first and second pair of tapes being free, a plurality of spaced transverse tapes secured to and extending between the first depending tapes, and a plurality of spaced transverse tapes secured to 55 and extending between the second depending tapes, whereby a diaper may have its ends folded over and under the transverse tapes at the front and the back of the garment to hold said diaper securely within the garment.
